[57] CLAIM

The ornamental design for a gun guitar, as shown and described.

DESCRIPTION

FIG. 1 is a front elevational view of a gun guitar showing my new design;

FIG. 2 is a side elevational view thereof;

FIG. 3 is a side elevational view taken from the opposite side of FIG. 2;

FIG. 4 is a rear elevational view thereof;

FIG. 5 is a front elevational view of a second embodiment of the guitar shown in FIG. 1;

FIG. 6 is a rear elevational view thereof;

FIG. 7 is a front elevational view of a third modified embodiment of the guitar shown in FIG. 1;

FIG. 8 is a side elevational view of a fourth embodiment of the guitar shown in FIG. 1;

FIG. 9 is a front elevational view thereof; and,

FIG. 10 is a side elevational view taken from the opposite side of FIG. 8.
